UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

AIR-COMPRESSOR FOR INTERNAL-COMBUSTION ENGINES.

1,236,187.

Specification of Letters Patent.

Patented Aug. 7, 1917.

Application filed December 26, 1913. Serial No. 808,843.

To all whom it may concern:

Be it known that I, HERMANN LEMP, a citizen of the United States, residing at Erie, county of Erie, State of Pennsylvania, have invented new and useful Improvements in Air-Compressors for Internal-Combustion Engines, of which the following is a specification:

In the operation of internal combustion engines having closed crank casings it is desirable to maintain the crank chamber under a slight vacuum to prevent the lubricating oil therein from working out through the joints and also to remove any exhaust 10 gases that may escape past the piston rings into said chamber. Some engines, notably those operating with crude oil on the high compression cycle, are provided with reciprocating air compressors for supplying low 15 pressure air for scavenging purposes, and high pressure air for injecting fuel into the combustion chamber against the compression pressure. Generally speaking the first stage of such a compressor is referred to as the 20 scavenging pump. It is not necessary of course to build the pump and compressor in one structure, but it is usually done for 25 simplicity and reduced cost.

My invention is directed especially to engines of the last mentioned type and has for its object to improve their construction and operation, whereby the said compressor, in addition to supplying the scavenging and fuel injecting or blast air, as it is commonly 30 called, is utilized to maintain a slight vacuum in the crank chamber. To prevent the compressor from sucking oil out of the crank chamber when so arranged, an oil separator 35 is located in the conduit through which the crank chamber air must flow on its way to the first stage or scavenging pump portion 40 of the compressor.

In the accompanying drawing which illustrates one of the embodiments of my invention is shown a portion of an engine provided with a reciprocating air compressor, several of the parts being shown in section.

1 indicates the base of the engine which contains a closed crank chamber 2. 3 indicates the main shaft of the engine having a crank 4 for actuating the air compressor by means of the connecting rod 5. Mounted on top of the base or crank casing is a receiver 6 of any suitable construction. Lo-

cated in the receiver is a reciprocating air compressor shown in dotted lines. It comprises a low pressure portion 7, commonly referred to as the scavenging pump, an intermediate pressure portion 8, and a high pressure portion 9 the latter supplying the blast air for injecting fuel into the combustion chambers of the working cylinders. The piston 7^a and the cylinder of the scavenging pump are both indicated by dotted lines. The scavenging pump is of a double acting type while the intermediate and high pressure portions of the compressor are single acting. The admission of air to the scavenging pump and the discharge therefrom into the receiver is controlled by the reciprocating valve 10, the latter being actuated by suitable means from the main shaft 3. The main supply of air to the scavenging pump is admitted to the supply chamber 11 through the screen 12 which is mounted directly above. In order to maintain a slight vacuum in the crank chamber to prevent lubricant from being forced through the various joints and also to carry off any exhaust gases which may leak into the crank chamber past the piston rings, a conduit 13 is provided in the receiver or elsewhere which opens at its lower end into the crank chamber, its other end opening into the supply chamber 11. Owing to the movements of the various cranks in the crank chamber the lubricating oil is agitated and any device sucking air out of the chamber is liable to carry with it more or less lubricant in the form of small particles or spray. To prevent this from entering the scavenging pump as far as possible, an oil separator is provided which is located in the vertical conduit 13. This separator comprises a casing 14 which is provided with a flange at its upper end, the latter resting on the top of the receiver. Located inside of the casing is a tube 15 the upper end of which is screwed into one end of the conduit 16, said conduit forming a continuation of the conduit 13 and opening into the air supply chamber 11. The walls of the casing 14 are so shaped as to form a Venturi tube, the throat 17 of which is formed by the walls of the casing 14 and the tube 15. The upper part of the casing is provided with orifices 18 through which air mixed with a certain amount of lubricant is free

to flow on the suction strokes of the piston of the scavenging pump. Owing to the fact that tube 15 is only open at its lower end, the flow of air passing through the orifices 5 18 has to change from an upward to a downward direction, and in passing through the throat 17 of the Venturi tube its velocity is largely increased. This causes the particles of oil to be projected downward 10 against the inclined lower wall 19 of the casing. In the wall is a small orifice 20 through which the lubricant is free to drop back into the conduit 13 and chamber 2. Due to the fact that this orifice is small in 15 cross section, the tendency for air to flow through it in an upward direction can be disregarded. After the air has passed through the separator, it flows through the conduit 16 and there unites with the fresh 20 air flowing through the screen 12 into the supply chamber. In other words, the screen and conduit 16 are arranged in multiple to supply air to the scavenging pump, the greater portion of the air, however, being 25 received through the screen 12. By properly proportioning the cross sectional area of the conduit 16 and the inlet area of the chamber 11 from the screen, any desired 30 vacuum can be maintained in the crank chamber 2. Generally speaking only a comparatively slight vacuum is necessary in the chamber 2 to prevent lubricant from working out through the various joints in the 35 crank casing.

I have shown my invention in connection with a two-cycle engine but it is not limited thereto since it can be utilized with four cycle engines in which case the working pistons will have the function on their suction 40 strokes as the piston 7.

In accordance with the provisions of the patent statutes I have described the principle of operation of my invention, together with the apparatus which I now consider 45 to represent the best embodiment thereof; but I desire to have it understood that the apparatus shown is only illustrative, and

that the invention can be carried out by other means.

What I claim as new and desire to secure by Letters Patent of the United States is:—

1. In an apparatus of the character described, the combination of an internal combustion engine having a closed crank casing containing lubricant for the engine, an air compressor driven by the engine and supplying air to it, said compressor having an air inlet and a valve controlling the same, and a conduit connecting the crank casing 55 to the inlet of the compressor at a point in advance of said valve as regards the flow of air, said compressor receiving air in parallel through said inlet and the conduit leading from the crank casing, whereby said 60 compressor serves to withdraw explosive gases from the crank casing and to maintain a slight vacuum therein to prevent the leakage of lubricant.

2. In an apparatus of the character described, the combination of an internal combustion engine having a closed crank casing containing lubricant for the engine, an air compressor driven by the engine and supplying air to it, said compressor having an 75 air inlet and a valve controlling the same, a conduit connecting the crank casing to the inlet of the compressor at a point in advance of said valve as regards the flow of air, said compressor receiving air in parallel through 80 said inlet and the conduit leading from the crank casing, whereby said compressor serves to withdraw explosive gases from the crank casing and to maintain a slight 85 vacuum therein to prevent the leakage of lubricant, and an oil separator through which the gases from the crank casing pass on their way to the compressor.

In witness whereof, I have hereunto set my hand this 19th day of December, 1913. 90
HERMANN LEMP.
